ABSTRACT

A drilling choke is controlled in a controlled pressure system. Pressure and position of the drilling choke are monitored. An adjustment to the position of the choke is determined based on the monitored pressure to control the drilling pressures. An actuation is produced of an actuator operably coupled to the choke to implement the determined adjustment. Rather than directly transferring, the actuation of the actuator is transferred with a transfer mechanism to motion of the choke in a non-linear relationship relative to the position of the choke. Generally, motion of the choke's internal trim (e.g., gate, ball, flapper, disc, etc.) is made quicker when near a fully opened position and is made slower when near a fully closed position. This reduces the need for strict precision for the motion. In the end, the monitored pressure is altered in response to the implemented choke adjustment.

MANAGED PRESSURE CONTROL SYSTEM WITH VARIABLE BUILT-IN ACCURACY

BACKGROUND OF THE DISCLOSURE

In managed pressure drilling (MPD) systems, drilling chokes or other forms of control valves are used to control the wellbore pressure and the flow rate coming out of a wellbore. The mechanism that opens or closes the chokes typically consists of either a hydraulic piston that slides axially under control of hydraulic pressure (from a hydraulic power unit) or under control of a worm gear jack screw (driven by a hydraulic or electric motor).

For example, FIG. 1A illustrates a drilling choke arrangement 10, such as used in managed pressure drilling. A hydraulic power unit (HPU) 14 feeds hydraulic pressure to a hydraulic motor 16, which turns a jack screw to turn a worm gear 26. An internal trim, such as a gate (not shown), within a drilling choke 20 is moved by the worm gear 26 to change an orifice for fluid flow in the choke 20 from the inlet 22 to the outlet 24. A control unit 12 couples to the hydraulic pressure unit 14 and to a position sensor 18. To choke the flow from the inlet 22 to the outlet 24, the control unit 12 actuates the pressure unit 14, motor 16, worm gear 26, etc. to adjust the choke's gate. Feedback from the position sensor 18 is used to monitor the position.

In this arrangement 10 as well as an arrangement that uses a hydraulic piston, the input motion of the actuator 16 that causes the choke 20 to open and close correlates with a direct linear movement of the choke's internal trim (i.e., gate) by design. As a result of the design of the actuator 16, the speed of the moving gate inside of the choke 20 will be the same throughout the time that the input motion is applied. This means that the closing speed of the choke 20 when there is a relatively high pressure drop across the choke 20 will be the same as the closing speed when the choke 20 is near the fully open position.

One obstacle to overcome when controlling pressure is trying to hold a specified wellbore pressure while operating with less than 4% range of available motion of the choke 20 for all required pressure holds during a typical field run. For instance, FIG. 1B graphs a choke pressure drop versus position plot 30 for an example implementation in which particular choke positions (as a percentage open) relate to corresponding pressure drops (psi) produced by a choke. As the graphed line 32 indicates, most of the pressure drop (i.e., about 150-psi to 700-psi) that can be produced with the choke may fall within a range 36 of choke position (e.g., about 32% to 36%) that is essentially 4% of the choke's total possible movement. Accordingly, in this instance, the choke will typically be operated within this 4% of choke movement as the choke is used to manage pressure. As will be evident, precise control of the choke position is required to achieve the desired pressure drop. In fact, a control system can reach a point where each successive increment of 0.1% of the choke gate motion to control the choke can cause a change of 50 psi pressure drop or more as the control system approaches the higher end of the pressure drop range.

When a control system is forced to move a choke at a constant rate along the full range of motion, a special emphasis must be placed on high precision pulses of control system input at the upper range of wellbore pressures. This requires the use of high precision machined components inside the choke or valve actuator as well as the HPU and further tweaking of the control system with periodic calibration to account for the loss of accuracy within the system that occurs over time. Several hundreds of man hours have

been spent fine tuning, calibrating, and replacing parts to obtain the final increment of accuracy that is required to pass function testing of systems.

The emphasis of designing MPD control systems up to this point has been focused on precision control within a small range of motion of the choke or valve. A majority of man hours of factory acceptance testing have been spent fine-tuning these control systems and inspecting and replacing mechanical parts in the HPU and choke to achieve the high degree of precision that is required to precisely control the wellbore pressure. For the current designs, the total valid range of pressure control adds up to approximately 4% of the total available gate motion. If the desired accuracy for managed pressure is +/-10 psi in terms of pressure, then the accuracy of the gate motion can be limited to +/-0.02% of the full range which comes to less than +/-0.0005 inches. This accuracy has been achieved with each new system, but it has come at the cost of hundreds of man-hours with each new factory acceptance test. Moreover, each MPD control system typically needs to be re-calibrated frequently to maintain the high level of control precision due to time-related deteriorating factors.

The subject matter of the present disclosure is directed to overcoming, or at least reducing the effects of, one or more of the problems set forth above.

SUMMARY OF THE DISCLOSURE

According to the present disclosure, a method of controlling a drilling choke in a drilling system includes monitoring a parameter in the drilling system and monitoring position of the drilling choke. An adjustment is determined to the position of the drilling choke based on the monitored parameter and the monitored position. An actuation of an actuator operably coupled to the drilling choke is produced to implement the adjustment. The actuation of the actuator is transferred with a transfer mechanism to motion of the drilling choke in a non-linear relationship relative to the position of the drilling choke. The monitored parameter is altered in response to the implemented adjustment of the drilling choke.

Monitoring the parameter in the controlled pressure system can involve monitoring the parameter including flow-in, flow-out, density, and standpipe pressure, and monitoring the position of the drilling choke can involve obtaining an indication of the position from a position sensor operably connected to the drilling choke. The adjustment to the position of the drilling choke determined based on the monitored parameter and the monitored position can involve correlating a change from the monitored position to a new position of the drilling choke relative to a change from a current value the monitored parameter to a new value for the monitored parameter. Altering the monitored parameter in response to the implemented adjustment of the drilling choke can include changing surface backpressure of the controlled pressure system.

The actuation of the actuator operably coupled to the drilling choke produced to implement the adjustment can include operating a hydraulic motor with a hydraulic power unit, operating an electric motor with a power supply, etc.

In transferring the actuation of the actuator with the transfer mechanism to the motion of the drilling choke in the non-linear relationship relative to the position of the drilling choke, the motion (e.g., speed) can be made quicker when near the position of being fully opened and can be made slower when near the position of being fully closed. In transferring the actuation of the actuator with the transfer

mechanism to the motion of the drilling choke in the non-linear relationship relative to the position of the drilling choke, the motion (e.g., displacement) can be made greater when near the position of being fully opened and can be made smaller when near the position of being fully closed.

Transferring with the transfer mechanism can involve transferring with the transfer mechanism operable between the actuator and the drilling choke. For example, the transfer mechanism can include a linkage operable between the actuator and the drilling choke, a crank and slider linkage operable between the actuator and the drilling choke, or a bell crank linkage operable between the actuator and the drilling choke. The transfer mechanism can be a gear arrangement, such as a planetary or elliptical arrangement, operable between the actuator and the drilling choke, can be a variable ratio chain and sprocket arrangement operable between the actuator and the drilling choke, or can be a variable transmission operable between the actuator and the drilling choke.

Transferring with the transfer mechanism can involve transferring with the transfer mechanism operable between a power source and the actuator. For example, the transfer mechanism can include a throttling valve operable between a hydraulic power source and a hydraulic motor of the actuator, a throttling valve operable between a hydraulic source of the power source and a hydraulic motor of the actuator and having a stem directly operated by movement of the choke, a drive operable between an electric power source and an electric motor of the actuator, or a control valve operable between a hydraulic power source and a variable speed hydraulic motor of the actuator. The transfer mechanism can include at least one control algorithm being operable to control the actuator according to the disclosed non-linear relationship.

According to the present disclosure, a programmable storage device having program instructions stored thereon can cause a programmable control device to control a drilling choke in a drilling system, as disclosed herein. The teachings of the present disclosure can apply to a drilling choke of a drilling system, as discussed above, and can apply to controlling a choke in other implementations.

According to the present disclosure, an apparatus for a pressure system includes a valve, a position sensor, an actuator, a controller, and a transfer mechanism. The valve is in operable communication with the pressure system. The position sensor is in operable communication with the valve and obtains position of the valve trim, and the actuator is in operable communication with the valve. The controller is in operable communication with the position sensor and the actuator. The controller receives an adjustment to the position of the valve trim and produces an actuation of the actuator to implement the received adjustment. The transfer mechanism is operable between the actuator and the valve and transfers the actuation of the actuator to motion of the valve trim in a non-linear relationship relative to the position of the valve trim.

The valve can be a choke, a needle valve, a ball valve, a gate valve, a globe valve, a plug valve, a disc choke with plates, a butterfly valve, or the like. As noted, the valve can be a drilling choke in fluid communication with a borehole. In this arrangement, the controller is operable to monitor a parameter in the pressure system and to monitor the position of the drilling choke. The controller determines the adjustment to the position of the drilling choke based on the monitored parameter and the monitored position and produces the actuation of the actuator operably coupled to the drilling choke to implement the adjustment.

The foregoing summary is not intended to summarize each potential embodiment or every aspect of the present disclosure.

5 BRIEF DESCRIPTION OF THE DRAWINGS

FIG. 1A illustrates a drilling choke, such as used in managed pressure drilling, controlled by a control unit, an actuator, and a position sensor according to the existing art.

10 FIG. 1B graphs an example implementation in which particular choke positions (as a percentage open) relate to corresponding pressure drops (psi) produced by a drilling choke.

15 FIG. 2A illustrates a controlled pressure drilling system according to the present disclosure.

FIG. 2B illustrates a process for controlled pressure drilling according to the present disclosure.

20 FIG. 3 illustrates an embodiment of a choke, such as used in controlled pressure drilling, controlled by a control unit, a power source, and an operational device according to the present disclosure.

FIGS. 4A-4B illustrate details of a non-linear transfer mechanism for control between a choke actuator and a gate for a choke according to the present disclosure.

25 FIGS. 5A-5B illustrate details of a second non-linear transfer mechanism for control between a choke actuator and gate for a choke according to the present disclosure.

FIG. 6A graphs comparative curves for a bell crank mechanism and a worm gear mechanism as a function of choke pressure drop relative to control motor revolutions.

30 FIG. 6B graphs comparative curves for the bell crank mechanism and the worm gear mechanism as a function of choke closing speed relative to time.

FIG. 6C graphs comparative curves for the disclosed transfer mechanism and the worm gear mechanism as a function of input motion relative to output motion.

35 FIG. 7A illustrates an operational device according to the present disclosure having a bell crank and a piston for control of a drilling choke.

FIGS. 7B-7D illustrate details of the bell crank and piston arrangement for control of a gate on a choke according to the present disclosure.

40 FIG. 8 illustrates an embodiment of a choke controlled by a control unit, an actuator, a position sensor, and a third non-linear transfer mechanism according to the present disclosure.

FIG. 9 illustrates another embodiment of the choke controlled by the fourth non-linear transfer mechanism according to the present disclosure.

FIGS. 10A-10B shown the fourth non-linear transfer mechanism of FIG. 9 in more detail.

45 FIG. 11 illustrates an embodiment of a choke controlled by a control unit, an actuator, a position sensor, and a fifth non-linear transfer mechanism according to the present disclosure.

FIG. 12A illustrates an embodiment of a choke controlled by a control unit, an actuator, a position sensor, and a sixth non-linear transfer mechanism according to the present disclosure.

50 FIG. 12B illustrates a detail of elliptical gears for the mechanism of FIG. 12A.

FIG. 13 illustrates an embodiment of a choke controlled by a control unit, an actuator, a position sensor, and a seventh non-linear transfer mechanism according to the present disclosure.

FIG. 14 illustrates an embodiment of a choke controlled by a control unit, an actuator, a position sensor, and a combination of non-linear transfer mechanisms according to the present disclosure.

DETAILED DESCRIPTION OF THE DISCLOSURE

FIG. 2A shows a closed-loop drilling system 50 according to the present disclosure for controlled pressure drilling. As shown and discussed herein, this system 50 can be a Managed Pressure Drilling (MPD) system and, more particularly, a Constant Bottomhole Pressure (CBHP) form of MPD system. Although discussed in this context, the teachings of the present disclosure can apply equally to other types of controlled pressure drilling systems, such as other MPD systems (Pressurized Mud-Cap Drilling, Returns-Flow-Control Drilling, Dual Gradient Drilling, etc.) as well as to Underbalanced Drilling (UBD) systems, as will be appreciated by one skilled in the art having the benefit of the present disclosure.

The drilling system 50 has a rotating control device (RCD) 52 from which a drill string 54, a bottom hole assembly (BHA), and a drill bit 58 extend downhole in a wellbore 56 through a formation F. The rotating control device 52 can include any suitable pressure containment device that keeps the wellbore in a closed-loop at all times while the wellbore 56 is being drilled.

The system 50 also includes a standpipe (not shown), rig pumps 84, mud tanks 82, a mud gas separator 80, and various flow lines, as well as other conventional components. In addition to these, the drilling system 50 includes an automated choke manifold 66 that is incorporated into the other components of the system 50, such as a control system 60 having a control unit 62 and a power source 64.

The control system 60 integrates hardware, software, and applications across the drilling system 50 and is used for monitoring, measuring, and controlling parameters in the drilling system 50. In this contained environment of the closed-loop system 50, for example, minute wellbore influxes or losses are detectable at the surface, and the control system 60 can further analyze pressure and flow data to detect kicks, losses, and other events. In turn, at least some operations of the drilling system 50 can be automatically handled by the control system 60.

To monitor operations, the control system 60 can use data from a number of sensors and devices in the system 50. For example, one or more sensors can measure pressure in the standpipe. One or more sensors (i.e., stroke counters) can measure the speed of the rig pumps 84 for deriving the flow rate of drilling fluid into the drillstring 54. In this way, flow into the drillstring may be determined from strokes-per-minute and/or standpipe pressure. Alternatively, a flowmeter 86, such as a Coriolis flowmeter after the rig pumps 84, can also be used to measure flow-in to the wellbore.

One or more sensors can measure the volume of fluid in the mud tanks 82 and can measure the rate of flow into and out of mud tanks 82. In turn, because a change in mud tank level can indicate a change in drilling fluid volume, flow-out of the wellbore may be determined from the volume entering the mud tanks 82.

The fluid data and other measurements noted herein can be transmitted to the control system 60, which can in turn operate drilling functions. In particular, the control system 60 can use the control unit 62 and power source 64 to operate the automated choke manifold 66, which manages pressure and flow during drilling and is incorporated into the drilling

system 50 downstream from the rotating control device 52 and upstream from the gas separator 80. Among other components, the manifold 66 has chokes 70, a flowmeter 68, pressure sensors (not shown), and other components. The controller or control unit 62 control operation of the manifold 66, and the power source 64 (e.g., hydraulic power unit and/or electric motor) actuate the chokes 70.

During operations, the system 50 uses the rotating control device 52 to keep the well closed to atmospheric conditions. 10 Fluid leaving the wellbore 56 flows through the automated choke manifold 66, which measures return flow (e.g., flow-out) and density using a flowmeter 68 installed in line with the chokes 70. Software components of the control system 60 then compare the flow rate in and out of the wellbore 56, 15 the injection pressure (or standpipe pressure), the surface backpressure (measured upstream from the drilling chokes 70), the position of the chokes 70, and the mud density, among other possible variables. Comparing these variables, the control system 60 then identifies minute downhole 20 influxes and losses on a real-time basis to manage the annulus pressure during drilling.

By identifying the downhole influxes and losses during drilling, for example, the control system 60 monitors circulation to maintain balanced flow for constant BHP under 25 operating conditions and to detect kicks and lost circulation events that jeopardize that balance. The drilling fluid is continuously circulated through the system 50, choke manifold 66, and the Coriolis flowmeter 68. As will be appreciated, the chokes 70 may fluctuate during normal operations 30 due to noise, sensor errors, etc. so that the system 60 can be calibrated to accommodate such fluctuations. In any event, the system 60 measures the flow-in and flow-out of the well, detects variations, and operates the chokes 70 to account for the variations. In general, if the flow-out is higher than the 35 flow-in, then fluid is being gained in the system 50, indicating a kick. By contrast, if the flow-out is lower than the flow-in, then drilling fluid is being lost to the formation, indicating lost circulation.

To then control pressure, the control system 60 introduces 40 pressure and flow changes to the incompressible circuit of fluid at the surface to change the annular pressure profile in the wellbore 56. To do this, the control system 60 uses the chokes 70 in the choke manifold 66 to apply surface backpressure within the closed loop, which can produce a 45 reciprocal change in bottomhole pressure. In this way, the control system 60 uses real-time flow and pressure data and manipulates the annular backpressure to manage wellbore influxes and losses.

In the control process, the control system 60 uses internal 50 algorithms to identify what event is occurring downhole and can react automatically. For example, the control system 60 monitors for any deviations in values during drilling operations, and alerts the operators of any problems that might be caused by a fluid influx into the wellbore 56 from the 55 formation F or a loss of drilling mud into the formation F. In addition, the control system 60 can automatically detect, control, and circulate out such influxes and losses by operating the chokes 70 on the choke manifold 66 and performing other automated operations.

FIG. 2B illustrates a process 200 for controlled pressure drilling according to the present disclosure. The control system (60) monitors various parameters of the drilling system (50), such as flow-in, flow-out, density, standpipe pressure, temperature, etc. (Block 202). The control system (60) also monitors position of the drilling choke(s) (70) (Block 204). The position information can be obtained from position sensor(s) operably connected to the drilling choke.

As drilling is performed, differences in the monitored parameters may indicate that operational changes are necessary, such as increasing or decreasing surface backpressure using the drilling choke(s) (70), so that decisions are continually made based on the monitored parameters (Decision 206). If adjustment to the choke(s) (70) is necessary, the control system (60) determines what adjustment to the position of the drilling choke is needed based on the monitored parameters and the monitored position (Block 208). As briefly described here, the control system (60) considers the current position of the choke(s), the current set point and correlates a change from the current position to a new position of the choke(s) relative to a desired change from a current set point of a monitored parameter to a new set point for the monitored parameter.

With the adjustment determined, the control system (60) produces actuation(s) of actuator(s) operably coupled to the drilling choke(s) (70) to implement the adjustment (Block 210). Depending on the actuator(s) used and the power source, the actuation(s) can be electrical, hydraulic, or the like.

In the implementation of the actuation(s), the transfer mechanism (100) of the present disclosure transfers the actuation(s) of the actuator(s) to motion of the drilling choke(s) (70) in a non-linear relationship relative to the position of the drilling choke(s) (70) (Block 212). As generally depicted here (Item 214), the non-linear relationship may tend to make the motion (i.e., speed) of the choke(s) (70) slower when near the position of being fully closed, whereas the motion (i.e., speed) of the choke(s) (70) may be quicker or faster by comparison when near the position of being fully opened. Likewise, the non-linear relationship may tend to make the motion (i.e., displacement) of the choke(s) (70) smaller when near the position of being fully closed, whereas the motion (i.e., displacement) of the choke(s) (70) may be larger by comparison when near the position of being fully opened. As noted, the additional control of the motion of the choke when near a more closed position is of particular interest with respect to controlling the flow, pressure, and the like through the choke.

In the end, the monitored parameter of the drilling system (50) can be properly altered in response to the implemented adjustment(s) of the drilling choke(s) (Block 216). For example, increased surface backpressure can be applied to produce an increase in bottomhole pressure and counter a fluid influx from the formation.

FIG. 3 illustrates an embodiment of a choke 70, such as a drilling choke used in managed pressure drilling, controlled by a control unit 62 and a power source 64. An operational device 100 for operating the choke 70 includes a position sensor 102, an actuator 110, and a non-linear transfer mechanism 120 according to the present disclosure. An internal trim, such as a gate (not shown) within the choke 70, is moved to change an orifice for fluid flow in the choke 70 from the inlet 72 to the outlet 74.

The position sensor 102 is in operable communication with the control unit 62 to provide position information of the choke 70, such as the position of the choke's internal gate or other internal trim mechanism (not shown). In general, the choke 70 can be a plug-style choke with trim that includes a gate and seat, such as used in a choke manifold of a drilling system. Other types of chokes could benefit from the teachings of the present disclosure so that reference to choke as used here can apply also to various types of valves, such as needle valve, ball valve, gate valve, globe valve, plug valve, disc choke with plates and alignable orifices, butterfly valve, etc.

The actuator 110 is in operable communication to the power source 64, which is operated by the control unit 62. Based on system controls and determinations, the control unit 62 receives and/or determines an adjustment for the position of the choke 70 and produces an actuation of the actuator 110 to implement the adjustment. As noted, the purpose of the adjustment can be to control surface backpressure in a managed pressure drilling system.

The non-linear transfer mechanism 120 is operable between the actuator 110 and the drilling choke 70. Instead of allowing the actuation and adjustment to be applied directly to the choke 70, the transfer mechanism 120 intermediates the transfer of the actuation from the actuator 110 to motion of the drilling choke 70 in a non-linear relationship relative to the position of the trim inside the drilling choke 70. The input from the transfer mechanism 120 is thereby applied to the choke 70 to produce motion of a variable orifice in the choke 70. (As noted, the internal trim in the choke 70 can be a gate, although other forms of trim can be used, such as ball, flapper, disc, etc.) In turn, the position sensor 102 detects the position information and feeds back to the control unit 62.

In this and other configurations disclosed herein, the position sensor 102 is preferably coupled directly to the gate 76 in the choke 70 to allow an accurate reading of the position for control purposes. The position sensor 102 can include a linear potentiometer, a Linear Variable Differential Transformer (LVDT), a proximity sensor, or any suitable device to detect position. Of course, other arrangements and different position sensors are possible.

The non-linear transfer mechanism 120 forces the non-linear relationship between the actuation and the resulting valve motion such that the valve motion occurs more quickly when near a fully opened position and occurs more slowly when near a fully closed position. As a result of the changed correlation, a broader range of controlled motion can be effectively used to control the wellbore pressure, thereby decreasing the necessary positional accuracy of the actuator 110 (e.g., hydraulic or electric motor) coupled with the control unit 62 and power source 64.

For example, the actuator 110 may be a hydraulic motor or an electric motor providing revolutions to actuate the choke 70. The non-linear transfer mechanism 120 can allow for five (5) revolutions of the motor 110 to control the applicable range of wellbore pressure instead of using just one (1) revolution. Consequently, the precision requirement for the actuator position can be relaxed by up to five (5) times.

Various types of non-linear transfer mechanisms 120 as disclosed herein can be used. In a first type, the transfer mechanism 120 can use an assembly of mechanical parts that force a nonlinear relationship between the input motion from the actuator 110 (e.g., rotational or linear motor or hydraulic cylinder) and the motion of the internal trim in the choke 70.

FIGS. 4A-4B illustrate a first non-linear transfer mechanism 120A of the present disclosure that uses a mechanical assembly. The mechanism 120A includes a crank and slider assembly having a rotating arm 122 with a hinged push rod 126 attached to a gate 76 of a choke 70 (shown simplified). The rotating arm 122 is coupled at an input point 123 to rotational input R from the actuator 110, which can be a hydraulic or electric motor, for example. Rotation of the rotating arm 122 about the input 123 transfers to the hinged push rod 126 via a moving pivot 124. The rod 126 couples with another moving pivot 128 to the gate 76 so that the rod

126 changes the rotary motion of the arm 122 into reciprocating motion of the gate 76 of the choke 70.

In this embodiment, the overall closing time of the choke 70 may remain the same as with a conventional design. However, with the choke 70 near an opened position (FIG. 4A), each increment of rotation of the arm 122 results in greater motion of the gate 76. By contrast, with the choke 70 near a closed position (FIG. 4B), each additional increment of rotation of the arm 122 results in less motion of the gate 76. Thus, the rotational input R of the actuator 110 is transferred by the mechanism 120A in a non-linear fashion to the motion of the gate 76, which gives more control to the operation of the choke 70.

FIGS. 5A-5B illustrate a second non-linear transfer mechanism 120B of the present disclosure that also uses a mechanical assembly. Here, the mechanism 120B includes a bell-crank linkage having a rotating arm 122 with a hinged push rod 126 attached to the gate 76 of the choke 70 (shown simplified). The rotating arm 122 is coupled at a pivot 127 to a linear input L from the actuator 110, which can be a piston or linear motor, for example. Rotation of the rotating arm 122 about a fixed pivot 125 transfers to the hinged push rod 126 via a moving pivot 124. The rod 126 couples with another moving pivot 128 to the gate 76. The linear input L from the actuator 110 rotates the arm 122, and the rod 126 changes the rotary motion of the arm 122 into reciprocating motion of the gate 76 of the choke 70.

In this embodiment, the overall closing time of the choke 70 may remain the same as with a conventional design. However, with the choke 70 near an opened position (FIG. 5A), each increment of rotation of the arm 122 results in greater motion of the gate 76. By contrast, with the choke 70 near a closed position (FIG. 5B), each additional increment of rotation of the arm 122 results in less motion of the gate 76. Thus, the linear input L of the actuator 110 is transferred by the mechanism 120B in a non-linear fashion to the motion of the gate 76, which gives more control to the operation of the choke 70.

In the mechanical assemblies of FIGS. 4A-5B, the mechanisms 120A-B have a fixed transfer relationship due to the mechanics of the components, and the particulars of the fixed mechanics involved can be configured for a given implementation. In this way, a given mechanism 120A-B with one of a plurality of different mechanics can be used on a given choke 70 to suit the requirements of an implementation. Differences in the geometry and sizes of the arms 122, 126 for example can achieve different control. Additionally, the pivot points 124, 128 can be adjustable on the arms 122, 126 to alter the mechanics, and/or arms 122, 126 of different lengths and geometries may be used interchangeably to alter the mechanics.

For comparative purposes, FIG. 6A graphs a plot 90A of a choke's pressure drop (psi) versus control motion revolution (count) for an existing worm gear mechanism (e.g., 26: FIG. 1A) alone and for an operational device (100) having a transfer mechanism (e.g., 120A-B: FIGS. 4A to 5B) of the present disclosure. The plot 90A shows the change of slope for two pressure curves 92A, 94A as they relate to a number of motor revolutions. The first pressure curve 92A is shown for the existing worm gear mechanism (26) of the prior art, such as shown in FIG. 1A and as is currently used in a choke actuator. This first pressure curve 92A is compared to a second pressure curve 94A for an operational device having the crank-slider or bell crank mechanisms (120A-B) of the present disclosure. (This example of the mechanism (120A-B) uses a 100:1 reducer gearbox installed between the motor (110) and the mechanism (120A-B) to reduce 26 revolutions

of the motor (110) into a 1/4 of a revolution of the rotating arm (122).) As the slope of the second curve 94A indicates, the mechanism 120A-B may provide approximately five (5) times more control resolution than the direct-drive worm gear mechanism (26) alone.

For comparative purposes, FIG. 6B graphs another plot 90B of choke closing speed (in/sec) versus time (sec) generally depicting the non-linear relationship. The plot 90B shows how the closing speed of the gate (76) does not vary with time for the existing worm screw mechanism (26: FIG. 1A) in curve 92B and shows how the closing speed of the gate (76) does vary with time for the disclosed crank-slider or bell crank mechanisms (120A-B) in curve 94B. The gate (76) closing speed (in/sec) is graphed relative to the choke closing position in time (sec) from opened to closed. As shown by curve 92B, the existing worm-gear mechanism (26) has a practically constant (linear) closing speed, which in this example is about 0.14-in/sec, as the gate (76) goes from an opened position to a closed position over a time period of 0 to about 13-sec. By contrast, the disclosed transfer mechanism (120A-B) shown by curve 94B has a varied closing speed that drops off over time, as the gate (76) goes from an open state to a closed state. The mechanism (120A-B) tends to make the motion (La, speed) of the choke (70) quicker or faster when near the position of being fully opened, whereas the motion (i.e., speed) of the choke (70) may be slower when near the position of being fully closed. This indicates that more refined closing can be achieved with the disclosed mechanisms (120A-B).

Looking at the relationship another way in a plot 90C of FIG. 6C, the non-linear relationship of the transfer mechanism (120A-B) can be viewed as actuation input from an actuator (i.e., input motion, degrees rotation of motor, linear displacement of piston, etc.) graphed relative to output of the choke (i.e., output motion, displacement of the choke's trim, etc.). For the worm gear arrangement, the transfer line 92C is constant in that each actuation input (degree rotation of the motor) results in output of the choke in a linear fashion as shown by the straight line. The correlation between the input and the output is linear, indicating that every increment (degree) of displacement of the actuator input produces a corresponding increment of displacement of the choke output.

By contrast, the transfer mechanism (120A-B) provides a different correlation between the input and output. As shown, the transfer line 94C initially has a steeper slope near the open state (0), which indicates that a given displacement of the input produces a greater displacement of the output. Yet, near the closed state (1), the slope of the transfer line 94C is less than the 1:1 ratio of the standard transfer line 92C. This lower slope indicates that a given displacement of the input results in a smaller displacement of the output. Accordingly, the non-linear relationship may tend to make the motion (i.e., displacement) of the choke(s) (70) smaller when near the position of being fully closed (1), whereas the motion (i.e., displacement) of the choke (70) may be larger by comparison when near the position of being fully opened (0).

Another operational device 100 in FIG. 7A combines the mechanical mechanism 120B shown in FIGS. 5A-5B with a hydraulic piston 150 as the actuator. The piston 150 attaches to the back side of the rotating arm 122. FIGS. 7B-7D show the bell crank mechanism 120B in conjunction with the piston 150 during stages of operation. The orientation and arrangement of the hydraulic piston 150 with respect to the rotating mechanism 120B is such that the initial driving motion from the sliding piston 150 yields a relatively larger

11

rotating motion than the final driving motion. The resulting variable rotating speed combined with the mechanical advantage of the rotating mechanism 120B provides additional resolution to the control as the gate (76) approaches the closed position.

FIG. 8 illustrates a choke 70 controlled by a control unit 62 and a power source 64 and operated by another operational device 100 according to the present disclosure. As shown, the operational device 100 for operating the choke 70 includes a position sensor 102, an actuator 110, and a non-linear transfer mechanism 120C. Here, the actuator 110 is a hydraulic motor powered by hydraulics from a hydraulic power unit (HPU) also referred to as the power source 64. The actuator 110 couples to the choke 70 with a worm gear arrangement 78 or the like, which transfers the rotation of the motor 110 into reciprocal movement of the internal trim (not shown) in the choke 70.

The non-linear transfer mechanism 120C includes a hydraulic throttling valve coupled to the hydraulics between the hydraulic motor 110 and the hydraulic power unit 64. The control unit 62 uses one or more control algorithms 104 that send control signals to the hydraulic throttling valve 120C coupled with the hydraulic motor 110. (If more than one control algorithm 104 is available, selection of a particular control algorithm 104 can be performed by the control unit 62 based on calibration, operating parameters, etc.) The controlled throttling from the signals causes the hydraulic motor 110 to speed up and slow down the motor revolutions according to feedback coming from the position sensor 102. Accordingly, these signals for controlling the speed of motor revolutions are used to achieve the purposes disclosed herein—namely slowing the closing speed of the internal trim (e.g., gate 76) in the choke 70 when near a fully closed position.

FIG. 9 illustrates a related configuration where a non-linear transfer mechanism 120C includes a hydraulic throttling valve coupled between the hydraulic motor 110 and the hydraulic power unit 64. Here, an operation stem of throttling valve 120C is physically moved by (directly operated by, attached to, or connected to) the stem on the choke 70, alongside the position indicator (not shown). The throttling valve 120C thereby moves with the movement of the choke 70 and correspondingly throttles the hydraulics to the motor 110.

FIGS. 10A-10B shows the hydraulic throttling valve 120C in more detail in two operating conditions (open—FIG. 10A and closed—FIG. 10B). The operation stem 160 of the valve 120C is physically moved by (or attached to) the choke stem (not shown) so the operation stem 160 can reciprocate inside a throttle housing 150. A throttling head 165 of the stem 160 can move relative to a flow restriction or orifice 155 to throttle flow from an inlet 152 (coupled to the power unit 64) to an outlet 154 (coupled to the motor 110).

In FIG. 10A, the throttling valve 120C is open with the throttling head 165 moved away from the flow restriction 155 for free flow of the hydraulics from the inlet 152 to the outlet 154. As the choke (70) moves closer to closing, however, the throttling valve's head 165 also moves closer to closing in the flow restriction 155, which slows down the flow of hydraulic fluid from the HPU 64 at the inlet 152 to the motor 110 at the outlet 154. This in turn slows down the closing speed of the gate (76) of the choke (70) according to the purposes disclosed herein.

FIG. 11 illustrates a related configuration where a non-linear transfer mechanism 120D includes a drive controller coupled between an electric motor 110 as the actuator and a

12

power supply 64 as the power source. Here, the control unit 62 uses one or more control algorithms 104 that send control signals to the drive controller 120D coupled with the electric motor 110. (If more than one control algorithm 104 is available, selection of a particular control algorithm 104 can be performed by the control unit 62 based on calibration, operating parameters, etc.) The controlled drive from the signals causes the electric motor 110 to speed up and slow down the motor revolutions according to feedback coming from the position sensor 102. Accordingly, these signals for controlling the speed of motor revolutions are used to achieve the purposes disclosed herein—namely slowing the closing speed of the internal trim (e.g., gate 76) in the choke 70 when near a fully closed position.

In the embodiments of FIGS. 11-12, the overall closing time of the choke's gate (76) can remain constant according to its particular design. However, the speed of the hydraulic or electric motor 110 driving the choke's gate (76) can be changed over time to allow a more linearized pressure over time profile near the closed position. As such, the closing speed can be adjusted to mimic what is graphed in FIG. 6B to produce better control of the resulting pressure drop similar to what is graphed in FIG. 6A.

Another non-linear transfer mechanism 120E according to the present disclosure shown in FIG. 12A can use a gear arrangement coupled between the actuator 110 and the choke 70. For example, the actuator 110 can be a hydraulic or electric motor that couples by a worm gear arrangement 78 to the choke 70 so that rotation of the motor 110 transfers to reciprocal movement of the internal trim (not shown) in the choke 70. The gear arrangement 120E alters the transfer of the rotation in a non-linear fashion according to the purposes disclosed herein. For example, the gear arrangement 120E can use a pairing of variable radii and/or variable pitch gears.

As shown in FIG. 12B, an example of a pair 130 of variable radii gears can include elliptical gears 132, 134. Using the pair 130 of the elliptical gears 132, 134 can change the rotational speed of the output gear 134 relative to the input gear 132, which would add more resolution to the control unit 62 as the internal trim in the choke 70 approaches the closed position.

As will be appreciated with the benefit of the present disclosure, other gear mechanisms can be used for the transfer mechanisms of the present disclosure. An arrangement having a chain between elliptical sprockets could be used in a manner similar to the planetary gears. Similarly, a continuously variable transmission can be used to make the transfer in the non-linear relationship.

Another operational device 100 in FIG. 13 for operating a choke 70 includes a position sensor 102, an actuator 110, and a non-linear transfer mechanism 120F according to the present disclosure. The actuator 110 is a hydraulic motor 110 with built-in variable speed. The variable speed motor 110 has a pilot port 112 accessed via a control valve 140 to actuate an internal mechanism in the motor 110 and change the required displacement of hydraulic fluid per revolution.

The control unit 62 uses one or more control algorithms 104 that send control signals to the control valve 140 coupled between the hydraulic power unit 64 and the pilot port 112 of the variable speed motor 110. (If more than one control algorithm 104 is available, selection of a particular control algorithm 104 can be performed by the control unit 62 based on calibration, operating parameters, etc.) The control valve 140 can be a solenoid operated three-way valve, as shown. The controlled pilot feed from the control valve 140 causes the variable speed motor 110 to speed up

and slow down according to feedback coming from the position sensor 102. Accordingly, this control for controlling the speed of motor revolutions are used to achieve the purposes disclosed herein—namely slowing the closing speed of the internal trim in the choke 70 when near a fully closed position. This configuration allows for finer control of the choke 70 at select positions based on feedback from the position sensor 102. The variable speed hydraulic motor 110 can also be implemented with any combination of the aforementioned embodiments.

A combination of the previously disclosed embodiments could be used together to enhance the control capabilities of a choke 70 at critical pressures. The gear arrangement 120E of FIG. 12A can be used in conjunction with the mechanisms 120A-B of FIGS. 4A-5B or can be coupled to the motor 110 of FIGS. 8-11.

As one particular example, FIG. 14 illustrates a choke 70 controlled by a control unit 62 and a hydraulic power unit 64 as the power source. The actuator 110 is a hydraulic motor in communication with the hydraulic power unit 64. A combination of the non-linear transfer mechanisms 120A-E of FIG. 4A through FIG. 12B can be used to transfer/control the actuation. In particular, a bell crank mechanism 120A as in FIGS. 4A-4B is coupled between the motor 110 and the choke 70 for adjusting motion of the choke's gate (76), and a gear box 120E having gears as in FIG. 12A is coupled between the bell crank mechanism 120A and the motor 110. The gear box 120E coupled between the motor 110 and the rotating arm of the mechanism 120E can alter the number of motor revolutions to move the gate (76) between fully-open to fully-closed in order to refine control as desired.

Finally, a hydraulic throttling valve 120C as in FIG. 8 can be operable between the power unit 64 and the hydraulic motor 110. One or more control algorithms 104 may be used by the control unit 62 to control the throttling valve 120C. The bell crank mechanism 120B and gear box 120E have a fixed transfer relationship built into the mechanics of the mechanisms. By contrast, the throttling valve 120C can have a selective transfer relationship based on the control algorithm used. As will be appreciated, these and other combinations of the various mechanisms 120 disclosed herein can be used for controlling the choke 70 according to the purposes disclosed herein.

The additional precision for the control system comes from a built-in mechanical component, or software algorithm or combination of the two that causes the choke's internal gate (76) to move more slowly as it nears the closed position. The use of an entirely mechanical device 100 to provide the additional range of control removes the need to have extra electrical components and software algorithms added to the design.

Although disclosed herein as applying to automated designs using powered actuation for a choke from a power source such as a hydraulic power unit or electric power supply, a manually operated choke can also benefit from the non-linear transfer mechanisms of the present disclosure. This may be especially evident for the mechanical assemblies disclosed herein where the rotational input R or the linear input L is provided by a manual device operated by personnel.

The foregoing description of preferred and other embodiments is not intended to limit or restrict the scope or applicability of the inventive concepts conceived of by the Applicants. It will be appreciated with the benefit of the present disclosure that features described above in accordance with any embodiment or aspect of the disclosed subject matter can be utilized, either alone or in combina-

tion, with any other described feature, in any other embodiment or aspect of the disclosed subject matter.

In exchange for disclosing the inventive concepts contained herein, the Applicants desire all patent rights afforded by the appended claims. Therefore, it is intended that the appended claims include all modifications and alterations to the full extent that they come within the scope of the following claims or the equivalents thereof.

10 What is claimed is:

1. A method of controlling fluid flow through a flow passage of a choke having an internal trim movable for opening and closing in relation to the flow passage, the method comprising:

15 monitoring position of the internal trim of the choke; receiving an adjustment to the position of the internal trim of the choke; producing an input displacement of an actuator, operably coupled by a non-linear mechanical link having a bell crank linkage to the internal trim of the choke, over a time period to implement the received adjustment by controlling an input speed of the input displacement provided by the actuator;

transferring the input displacement of the actuator, using the bell crank linkage of the non-linear mechanical link operably coupled between the actuator and the internal trim of the choke, to an output displacement of the internal trim of the choke in a non-linear relationship over the time period by: making the output displacement mechanically quicker in output speed than the controlled input speed when the internal trim is near a first position of being fully opened in relation to the flow passage, and making the output displacement mechanically slower in the output speed than the controlled input speed when the internal trim is near a second position of being fully closed in relation to the flow passage; and altering the position of the internal trim of the choke in response to the implemented adjustment.

2. The method of claim 1, wherein the choke is a drilling choke in a drilling system, the method comprising:

monitoring a parameter in the drilling system; determining an adjustment to the position of the internal trim of the drilling choke based on the monitored parameter and the monitored position; altering the monitored parameter by altering the position of the internal trim of the choke in response to the implemented adjustment of the internal trim of the drilling choke.

3. The method of claim 2, wherein monitoring the parameter in the drilling system comprises monitoring the parameter including flow-in of the fluid flow into the borehole, flow-out of the fluid flow out of the borehole, density of the fluid flow, and standpipe pressure of the fluid flow in a standpipe to the borehole.

4. The method of claim 2, wherein determining the adjustment to the position of the internal trim of the drilling choke based on the monitored parameter and the monitored position comprises:

determining a parameter change from a current set point value to a new set point value for the monitored parameter in the drilling system; and correlating a position change from a current position to a new position of the internal trim of the drilling choke relative to the parameter change from the current set point value to the new set point value for the monitored parameter.

15

5. The method of claim 1, wherein monitoring the position of the internal trim of the choke comprises obtaining an indication of the position from a position sensor operably connected to the choke.

6. The method of claim 1, wherein producing the input displacement of the actuator comprises:

operating a hydraulic motor with a hydraulic power unit;
or
operating an electric motor with a power supply.

7. The method of claim 1, wherein the non-linear mechanical link comprises: a gear arrangement connected to the bell crank linkage operable between the actuator and the internal trim of the drilling choke; a variable transmission connected to the bell crank linkage operable between the actuator and the internal trim of the drilling choke; or a combination thereof.

8. The method of claim 7, wherein the gear arrangement comprises a pairing of variable radii gears, a pairing of variable pitch gears, or a pairing of elliptical gears.

9. The method of claim 1, wherein producing the input displacement of the actuator further comprises: powering a power source for powering the actuator, and transferring, with a throttle operable between the power source and the actuator, the power of the power source to the actuator.

10. The method of claim 9, wherein the throttle comprises: a throttling valve operable between a hydraulic source of the power source and a hydraulic motor of the actuator; a throttling valve operable between a hydraulic source of the power source and a hydraulic motor of the actuator and having a stem directly operated by movement of the valve; a drive operable between an electric source of the power source and an electric motor of the actuator; a control valve operable between a hydraulic source of the power source and a variable speed motor of the actuator; at least one control algorithm being operable to control the actuator; or a combination thereof.

11. An apparatus for a pressure system, the apparatus comprising:

a valve in operable communication with the pressure system, the valve having a flow passage for communicating fluid flow and having an internal trim movable for opening and closing in relation to the flow passage to choke the fluid flow;

a position sensor in operable communication with the valve and obtaining position of the internal trim of the valve;

an actuator in operable communication with the valve; a controller in operable communication with the position sensor and the actuator, the controller receiving an adjustment to the position of the internal trim of the valve; and

a non-linear mechanical link having a bell crank linkage operably coupled between the actuator and the internal trim of the valve,

wherein the controller controls an input speed of the input displacement provided by the actuator to produce an input displacement of the actuator over a time period to implement the received adjustment, and

wherein to transfer the input displacement of the actuator to an output displacement of the internal trim of the valve in a non-linear relationship over the time period, the non-linear mechanical link makes (i) the output displacement mechanically quicker in output speed than the controlled input speed when the internal trim is near a first position of being fully opened in relation to the flow passage, and (ii) the output displacement mechanically slower in the out-

16

put speed than the controlled input speed when the internal trim is near a second position of being fully closed in relation to the flow passage, and wherein the position of the internal trim of the choke is altered in response to the implemented adjustment.

12. The method of claim 2, wherein altering the monitored parameter in response to the implemented adjustment of the drilling choke comprises changing surface backpressure of the drilling system.

13. The apparatus of claim 11, wherein the valve is selected from the group consisting of a choke, a needle valve, a ball valve, a gate valve, a globe valve, a plug valve, a disc choke with plates, and a butterfly valve.

14. The apparatus of claim 11, wherein the valve comprises a drilling choke in fluid communication with a bore-hole; and wherein the controller is operable to:

monitor a parameter in the pressure system;
monitor the position of the internal trim of the drilling choke;

determine the adjustment to the position of the internal trim of the drilling choke based on the monitored parameter and the monitored position; and

produce the output displacement of the actuator operably coupled by the non-linear mechanical link to the internal trim of the drilling choke to implement the adjustment.

15. The apparatus of claim 11, wherein the mechanical link further comprises: a gear arrangement connected to the bell crank linkage operable between the actuator and the internal trim of the valve; a variable transmission connected to the bell crank linkage operable between the actuator and the internal trim of the valve; or a combination thereof.

16. The apparatus of claim 11, further comprising:
a power source for powering the actuator; and
a throttle operably coupled between the power source and the actuator,

wherein the controller controls transfer of the power of the power source to the actuator with the throttle.

17. The apparatus of claim 16, wherein the throttle operable between the power source and the actuator comprises: a throttling valve operable between a hydraulic source of the power source and a hydraulic motor of the actuator; a throttling valve operable between a hydraulic source of the power source and a hydraulic motor of the actuator and having a stem directly operated by movement of the valve; a drive operable between an electric source of the power source and an electric motor of the actuator; a control valve operable between a hydraulic source of the power source and a variable speed motor of the actuator; at least one control algorithm being operable to control the actuator; or a combination thereof.

18. A method of controlling fluid flow through a flow passage of a choke having an internal trim movable for opening and closing in relation to the flow passage, the method comprising:

monitoring position of the internal trim of the choke;
receiving an adjustment to the position of the internal trim of the choke;

producing an input displacement of an actuator, operably coupled by a non-linear mechanical link having a bell crank linkage to the internal trim of the choke, over a time period to implement the adjustment by controlling an input extent of the input displacement provided by the actuator;

transferring, using the bell crank linkage of the non-linear mechanical link operably coupled between the actuator and the internal trim of the choke, the input displace-

17

ment to an output displacement of the internal trim of the choke in a non-linear relationship over the time period by:

making the output displacement mechanically greater in output extent than the controlled input extent when the internal trim is near the position of being fully opened in relation to the flow passage, and making the output displacement mechanically smaller in the output extent than the controlled input extent when the internal trim is near the position of being fully closed in relation to the flow passage; and altering the position of the internal trim of the choke in response to the implemented adjustment.

19. The method of claim **18**, wherein monitoring the position of the internal trim of the choke comprises obtaining an indication of the position from a position sensor operably connected to the choke.

20. The method of claim **18**, wherein producing the input displacement of the actuator comprises:

operating a hydraulic motor with a hydraulic power unit; or

operating an electric motor with a power supply.

21. The method of claim **18**, wherein the choke is a drilling choke in a drilling system, the drilling choke having the flow passage for communicating drilling fluid flow, the drilling choke having the internal trim movable for opening and closing in relation to the flow passage to choke the drilling fluid flow through the flow passage, the method comprising:

monitoring a parameter in the drilling system;

18

determining an adjustment to the position of the internal trim of the drilling choke based on the monitored parameter and the monitored position; and altering the monitored parameter by altering the position of the internal trim of the choke in response to the implemented adjustment of the internal trim of the drilling choke.

22. The method of claim **21**, wherein monitoring the parameter in the drilling system comprises monitoring the parameter including flow-in of the drilling fluid flow into the borehole, flow-out of the drilling fluid flow out of the borehole, density of the drilling fluid flow, and standpipe pressure of the drilling fluid flow in a standpipe to the borehole.

23. The method of claim **21**, wherein determining the adjustment to the position of the internal trim of the drilling choke based on the monitored parameter and the monitored position comprises:

determining a parameter change from a current set point value to a new set point value for the monitored parameter in the drilling system; and

correlating a position change from a current position to a new position of the internal trim of the drilling choke relative to the parameter change from the current set point value to the new set point value for the monitored parameter.

24. The method of claim **21**, wherein altering the monitored parameter in response to the implemented adjustment of the drilling choke comprises changing surface backpressure of the drilling system.
